UNITED STATES PATENT OFFICE.

SAMUEL HEDGES, OF WEST LIBERTY, WEST VIRGINIA.

SEAT FOR WAGONS OR AGRICULTURAL MACHINES.

SPECIFICATION forming part of Letters Patent No. 364,716, dated June 14, 1887.

Application filed January 28, 1885. Renewed December 13, 1886. Serial No. 231,491. (No model.)

To all whom it may concern:

Be it known that I, SAMUEL HEDGES, a citizen of the United States, residing at West Liberty, in the county of Ohio and State of West Virginia, have invented certain new and useful Improvements in Seats for Vehicles, of which the following is a specification, reference being had therein to the accompanying drawings.

My invention relates to a pivoted adjustable seat for vehicles, and is suitable for farm-wagons, sulky-plows, mowers, &c.; and it consists in certain improvements in the construction of the same, as hereinafter described, and specifically set forth in the claims.

Like letters represent like parts in all the figures.

Figure 1 is a side view of my improved seat. Fig. 2 is a rear view of the same. Fig. 3 is a perspective view of the screw and lever-carrying arm detached from the seat and its support. Fig. 4 is a perspective view of the bearing-plate of the seat, and Fig. 5 is a perspective view of the clamp shown in Figs. 1 and 2.

In the drawings, A represents the seat provided with pendent perforated lugs a axially on its under side, by which it is supported and pivoted on the rod B. This rod also passes through upwardly-projecting lugs c on the front and rear ends of the flat bearing-plate C.

The rod B is provided with a head on its forward end and a nut on the rear end, to facilitate the removal of the seat when desired, and it is located directly beneath the middle portion of the seat A; hence the seat is adapted to oscillate laterally on the rod B. When a vehicle passes along a hill-side or other inclined surface, and is partly tilted, its seat becomes also inclined laterally; but it is desirable that it be kept horizontal laterally for the ease and comfort of the driver, and also his safety. This is accomplished by my construction, as follows: The spring or seat-support D, attached at its forward end to the vehicle by bolts, or by any well-known means, has its rearwardly-extending end made to pass immediately under the bearing-plate C. A clamp-plate, E, provided with four upwardly-extending arms, E', located at its four corners, is suspended from the top of the plate C, the ends of the arms E' being bent inwardly at E' over the edges of the plate C. The clamp-

plate E is also provided in the middle thereof with a screw-threaded perforation to receive a clamping-screw, e, that passes upwardly through the clamp-plate E, and also through a laterally-extending arm, F, and presses against the washer G, receiving the end of the screw, as shown in Fig. 2. This washer G is located under the spring D, and is provided with shoulders that enter between the four upward arms E' of the clamp E, and prevents it from getting out of position. The arm F is provided at its outer end with a perforated boss, F', screw-threaded to receive a screw, H, having a double-V thread or a square thread. Said screw is provided at its lower end with a ball-shaped point, H', which can turn freely in a cavity or undercut groove in the outer end of the arm I' of a lever, I, pivoted at f to two lugs, F'', pendent from the arm F.

The screw H is turned by means of a crank-handle, H'', at its upper end. The pivoted lever I extends first downward under its pivot f and then toward the right-hand side of the seat, and to the end thereof there is pivoted by a bolt, f', an upwardly-extending rod, J, having forked ends to straddle the lever I' at one end, while at the upper end it straddles a lug, a', projecting from the side of the seat, and is pivoted thereto by a bolt, f''. The upwardly-extending rod J acts as a support or brace for the seat A, and in connection with the lever I and screw H, permits it to be kept level. The arm F, clamp E, and upper bearing-plate, C, may be made in one piece of metal, as represented in Fig. 3, and may be substituted for the above-named separate parts to lessen the number of pieces and facilitate the assembling of the devices used with my improved seat. The under lever, I, in place of being made angular or Z-shaped, as shown in Fig. 2, may be made straight by having the lugs F'' of such length that said lever will clear the parts under the bottom of the seat.

Having now fully described my invention, I claim—

1. The combination of a laterally-oscillating seat, the pivot-rod B, fixed parallel to the general line of motion of the vehicle, of which said seat forms a part, the lugs or support a for the seat, with a plate, C, provided with upwardly-extending lugs c, seat-support D,

clamp E, arm F, and clamping-screw e, substantially as and for the purpose described.

2. The combination of a laterally-oscillating vehicle-seat, the screw-carrying arm F, and a screw, H, having a handle attached, with the pivoted lever I and rod J, substantially as and for the purpose described.

3. The combination of the seat A, screw H, screw-carrying arm F, and lever I, pivoted to the arm F, and having a groove at one end to receive the end of the screw and at the other end the rod J, pivoted to the seat, substantially as and for the purpose described.

4. The combination of a seat-support, B, a screw-carrying arm, F, and plate C, clamped thereto, with the bent lever I and rod J, substantially as and for the purpose described.

In testimony whereof I affix my signature in presence of two witnesses.

SAMUEL HEDGES.
